UNITED STATES PATENT OFFICE.

CLINTON E. LARRABEE, OF BINGHAMTON, NEW YORK, ASSIGNOR TO INTERNATIONAL TIME RECORDING COMPANY OF NEW YORK; A CORPORATION OF NEW YORK.

RECORDER FOR REGISTERING LOCKS.

1,327,334.

Specification of Letters Patent.

Patented Jan. 6, 1920.

Application filed April 7, 1919. Serial No. 288,080.

To all whom it may concern:

Be it known that I, CLINTON E. LARRABEE, a citizen of the United States, residing at Binghamton, in the county of Broome and State of New York, have invented certain new and useful Improvements in Recorders for Registering Locks, of which the following is a full, clear, and exact description.

There are at the present time in use, and 10 there have been proposed a variety of recording locks, distinguished in general, by the combination with the lock mechanisms proper of means for operating a more or less remote mechanism over suitable circuits 15 to record the particular key used to operate the lock; the particular door or the special lock attached to it which is operated, a character of figure which indicates whether the key was inserted from the outside or the 20 inside, and other data of a like useful nature.

The invention upon which the present application for Letters Patent is based is an improvement in the recorders or the means 25 employed in such systems for receiving and recording in permanent form, the information of the nature referred to.

The mechanism of my improved instrument is designed to be operated either manually or electrically to record the data desired. It has provision for recording the 30 signature of an employee in conjunction with the time at which the signature was made, and other items of information, such as marks or symbols indicating the door in 35 which a lock is located, the particular key used and such others as have been specified above. It is so arranged that when being used as a signature or autograph recorder, 40 certain parts only are operative while the others are locked against operation, while, when used in conjunction with the automatic mechanism of the lock, the previously locked parts are brought into operation as 45 well as such of the other parts as may be necessary.

The apparatus is further designed in such manner and form that when used in coöperation with a lock to automatically record, it 50 cannot be operated manually and vice versa, and it may be provided with means for giving a signal or alarm when operated at certain predetermined or unusual times.

The invention resides in the construction 55 of the elements and in their novel combi-

nation to form a more effective and practical mechanism and one more dependable and reliable in operation than those which preceded it, and hence no further general statement of its nature and purpose will be 60 required for its proper comprehension.

In the accompanying drawings, which illustrate the details of the mechanism,

Fig. 1 is a side view looking from the right, with parts of the casing removed, of 65 the recorder proper.

Fig. 2 is a sectional view of the same mechanism on line 2—2 of Fig. 4.

Fig. 3 is a top plan view of the recorder mechanism with the printing elements re- 70 moved.

Fig. 4 is a front view in elevation of the apparatus with certain parts omitted.

Fig. 5 is a detail view of parts of the device which are designed for setting the 75 type segments for printing.

Fig. 6 is an enlarged view, partly in elevation and partly in section, of the operative recording mechanism.

Fig. 7 is a view of a portion of one of the 80 slips printed by the recorder, and

Fig. 8 is an electrical diagram of the system including a plurality of recording locks.

The character of the locks used for operating the recorder is not of the essence of 85 this invention, and may be greatly modified. In a copending application, filed November 11, 1918, Serial No. 261,976, I have shown in detail such a lock and reference may be had 90 to the drawings and descriptions of that case for such information as may be required as to the actual construction of such locks.

In the apparatus of the present case the 95 parts are properly associated in a casing 1, having an inclined front 2, with a window or opening 3 therein which may be either normally open or stand normally closed by a shield 4, adapted to be moved over a 100 platform 5 over which is carried a record sheet or strip of paper 6 from a supply reel 7 to take up reel 8. The construction and mode of operation of the device when operated manually may be first described.

The main drive shaft is indicated by the 105 numeral 9, and for hand operation it is provided with a suitable crank 85 Fig. 4. Assuming for the moment that, by means hereinafter to be described, the type on wheel 110

40 to indicate time have been set to printing position by the time mechanism, the turning of the shaft in a counter clockwise direction through a given arc rotates an arm 5 10 fast to the shaft to which is pivoted a link 11 connecting said arm to a bell crank lever 12 on a shaft 13, the end of which is formed as a cam which engages a roller 14 on a lever 15, see Figs. 4 and 6.

10 A lever 16, see Figs. 5 and 6 is fixed to a hub 78 on shaft 17 and having an extension 79 which interlocks or engages with a sleeve 81, which carries a projection 19 that is in the path of a bent projection 83 from one 15 of the plates 20 that carry the printing pad 21. The lever 16 has a bent or turned over end 18, as shown, which lies over the lever 15, and by the movement of the latter sleeve 81 is rotated clockwise and this operates 20 through the projection 19 to throw the spring actuated plate or lever 20 carrying the printing pad 21 against the strip 6 and thus print the set up characters which are in the printing position.

25 On a shaft 27 is mounted so as to turn thereon, a lever 26, connected by a link 30 to a pawl mechanism 31 which when shifted operates to turn a ratchet wheel 32 about a shaft 33, in a counter-clockwise direction, 30 and to thereby wind up the paper reel 8 and feed the record sheet. Movement of sufficient extent to feed the paper so as to receive autographs is accomplished by the mechanism which opens the shutter 4.

35 On a shaft 27 is fixed a crank 28 to which crank is pivoted a link 29 that engages by a slot and pin connection with the lever 12, so that when the main shaft 9 is rotated the shaft 27 is also turned and in an anti-clockwise direction. Normally the window 3, in 40 the inclined top of the casing is closed by the sliding plate or shutter 4, but this plate is connected by a link 38, with the lever or crank 28, so that when an employee operates the instrument manually, the window is 45 opened to permit him to write his name on the record strip. It will be observed that by reason of the pin and slot connection between the lever 12 and the link 29 that 50 shutter is not withdrawn until the main shaft 9 has been turned through a substantial arc.

Keyed to the shaft 27 is an arm or lever 55 and in the path of the end of this arm is a projection or turned over portion 96 of the lever 26. Hence when the shaft 27 is turned in an anti-clockwise direction by the lever 28 and link 29, this arm engages the said turned over portion 96 of lever 26 and the 60 latter is moved through a substantial arc and thereby imparts a feed movement to the paper, ample to receive another autograph.

The feed movement of the paper produced by the movement of the lever 26, also feeds 65 the inking ribbon 22, which is carried by

spools 23 on vertical spindles 24 having gear wheels 25 at their lower ends by the means shown in Figs. 1 and 2 which comprises a pawl 34 pivoted to the lever 26 and operating on a ratchet wheel 35 mounted on a shaft 36, on the ends of which are gears 37. Figs. 1, 2 and 4 which engage alternately with the gears 25 on spindles 24 and thereby feed the inking ribbon step by step.

The time type wheels 40 are shown in Fig. 3 as being in gear with a spindle 39, which is driven by a suitable clock which is not shown in the drawing, but in order that a minute type may be presented squarely to the printing pad whenever the latter is operated, I employ what is termed an alining pawl 41, Fig. 2, which is mounted on a lever 42 and connected by a link 43 to the lever 20. The latter being oscillated to effect the printing therefore moves the pawl 41 which engages with a ratchet wheel 44 and thereby alines up the minute type wheel so that whole minutes only will be printed and not parts of one or two adjacent numbers.

As above stated, the apparatus is so arranged that while being manually operated it can not be operated by the lock mechanism. This may be accomplished by the means shown in Fig. 5. A lever 45 is pivoted in the instrument in such position that an insulating pin 46 carried by it rides on a cam 47 on the main shaft 9. When the main shaft is turned from its normal position the cam raises the lever 45 and causes it to close two contacts 48 which complete a circuit to the lock or locks connected with the recorder and locks the mechanism thereof so that it can not be operated until the completion of the manual operation of the recorder, when the circuit between contacts 48 is again broken.

By the above described use of the device the employees of a store or any place of business may register their arrival or departure and the time thereof, but the primary object of the apparatus is to record the exact time when any given lock was operated either to open the place or lock it up, and who was responsible for doing these things. The operation as controlled by one or any number of locks will therefore be described.

The device is provided, conveniently, with three type controlling magnets 49, although a greater or even less number might be used, and these are in circuits from one or more locks, the operation of which sends to said magnets one or more current impulses which set the type segments to bring the proper characters thereon to printing position. Each of these magnets 49 has an armature 50 carried by a pivoted lever 51 with an arm thereon carrying a pivoted pawl 52. A current impulse in a magnet shifts the pawl 52 to the position shown in Fig. 5, and on the cessation of such impulse a spring 53

90

95

100

105

110

115

120

125

130

causes said pawl to engage with a tooth of a segment 54 integral with the type segment 55, and thereby brings a new type to the printing position. A retaining pawl 56 normally engages the teeth of the segment 54 and prevents its return until after the printing operation, when a cam 57 on a shaft 58 engages a bell crank lever 59 one end of which engages with a pin 60 on a lever 61, 10 and which in its movement engages and releases the retaining pawl and also engages with the arm of the armature 51 and lifts the pawl 52 off the toothed segment so that the type segment is restored to its normal position after each cycle of operation.

The type segments for each magnet are similar in construction and operation. The insertion of a given key into a given lock from a given side of the door may, for example 20 send four impulses to one magnet to represent the key used, two impulses to another magnet to indicate the lock operated, and one impulse to the third magnet to indicate that the key was inserted from the outside of the door. These signals set up the respective type segments in proper position to print the data, and after the printing is effected all the parts resume their normal positions.

30 After the proper impulses have been sent from and by the lock mechanism to the type setting magnets 49, and the type segments have been shifted so as to bring the proper type thereon into the printing position, a single impulse is sent from the lock to a magnet 62. This magnet, when energized, attracts its armature 63 which carries an insulating plate or bar 64 that engages and brings into contact with each other the two 40 terminals 65 that close the circuit to a motor 66 mounted in the lower part of the recorder casing. As this impulse is momentary only, a pivoted pawl 67, with a latching end, engages a projection on the armature 63 and holds the latter in attracted position and the terminals 65 in contact until the shaft 58 has made a complete revolution, when the latch is released by a projection or cam 69 engaging the end of the 50 latch 67 and thus releasing the armature and permitting the terminals 65 to separate.

The power for operating the recorder when operated by the lock mechanism is furnished by this motor 66. A gear 71 on the motor shaft imparts rotation to a vertical shaft 72, and in turn by a worm 73 imparts rotation to the shaft 58. To one end of this shaft there is eccentrically connected a link 74 which is pivoted to a lever 75, like the corresponding end of the lever 12, is formed as a cam that works on a pin 76 on a plate 77, see Figs. 1 and 6, that is designed to perform the same printing operation as plate or lever 15, and in the same way. As 65 the motor shaft makes one complete revolu-

tion for each cycle of operation the link 74 and lever 75 are moved back and forth and produce the same movement of the second printing pad as is effected with respect to pad 21 by the manual operation of the 70 shaft 9.

Manifestly, when operated manually as an autograph recorder, the instrument should record or print from the time type wheels only, but when operated by a lock 75 it should print from both the time type wheels and the indicating segments. This is accomplished by the means shown most clearly in Fig. 6. In this figure, as has been set forth, the plate or lever 15 is fixed to 80 the hub 78 with the extension 79, which turns freely on the shaft 17. The said hub, by its interlocking engagement with sleeve 81, operates the printing pad for the time type wheels only when the pin 14 is engaged 85 by the cam end of lever 12 there being no connection between those parts and the shaft 17.

On the other hand, should the lever 75 be operated by the lock mechanism, the pin 76 90 is engaged which moves the armature plate 77 and thus engages a bent lever 90 fast to the shaft 17, which is thereby rotated. The shaft not only carries a projection 86, which engages with a stop 87 on one of the plates 95 or lever 88 connected with the pad for the indicating segments, similar in all respects to the projection 19 and stop 83 of Fig. 5 and thereby operates that pad, but the shaft 17 also carries a similar projection 82 that 100 engages a stop 91 on one of the plates connected with the printing pad for the time type wheels, and operates that pad also. The several projections and stops above described are not illustrated in detail except 105 that in Fig. 5, but they are all similar in general construction and may be very greatly modified if necessary.

When the recording mechanism is operated by the lock, the paper strip must be fed, 110 but not to the same extent as by the operation of the manual or autograph mechanism. This is accomplished by the means shown in Fig. 2. When the shaft 13 is rotated by the swinging of lever 75, Fig. 1, an arm 92 115 fixed to said shaft and which carries a pin 93 in its end, travels in a slot in the end of a link 94. This link is pivotally connected to the lever 26, turning about the shaft 27 as a center. By reason of the slot and pin 120 connection the movement thus imparted to the lever 26 is not as extended as when it is moved by the crank arm 95, and a correspondingly shorter feed movement is therefore imparted to the papers.

The above description covers so far as is necessary for one skilled in this art the knowledge to construct and to operate the recorder. It remains therefore to describe, only in such general way as is requisite to 130

an understanding of the present invention, the nature of the system with which the device is more particularly designed to be used. For this purpose reference may be had to Fig. 8.

In this figure A indicates one lock, B another or others, and C the recorder which has been described in detail above. At the lock are the necessary terminals for the circuits that carry to the recorder the current impulses for operating the three magnets 49, such magnets having a common return wire. The outgoing circuits are numbered 100, 101, and 102, and the common return by 103.

15 In addition to these circuits there are also those which lead to the group of devices at the upper right hand corner of the sheet including a circuit 105, for the motor 66, the locking and the non-interfering circuits.

20 It has been explained that when an employee turns the shaft 9 to operate the recorder manually that a circuit to the lock is closed by the cam 47 that prevents the lock from being operated by a key until after 25 the manual operation is complete. To provide for the converse of this, and prevent manual operation while a key is being turned in the lock, I employ an electro-magnet 109, Fig. 5, which operates a pivoted 30 armature lever 110 that when the magnet is energized engages a notch in the cam 47. Whenever a key is inserted in a lock and turned it closes contacts in the lock that complete a circuit 111 including the magnet 35 109, and so locks the main shaft 9 against rotation by hand until the key has been turned back and withdrawn.

Between the two wires 106 and 107, the former connected with the lock mechanism 40 and the other to the recorder terminal from the in and out magnet 49, is a switch 108 and during such hours as the lock should not be operated at all a plug may be inserted 45 in this switch so that a current will be sent over this circuit whenever a key is inserted in the lock from either side. This circuit may lead to a burglar alarm station at any 50 convenient place and set off an alarm which gives notice that an unauthorized use is being made of the lock.

It will be understood that except so far as their respective functions are concerned the elements shown and described herein as making up this system may be modified indefinitely in construction.

What I claim is:

1. A manually and automatically operated recorder, comprising in combination, a series of time indicating type wheels, a printing 60 pad, a platen for taking impressions on a strip of paper therefrom, a device for manually operating the same, feeding means for the paper which at each manual operation feeds the strip sufficiently to receive the autograph of the operator in addition to the

time record, a set of indicating type wheels, a printing pad therefor, circuits from such a device as a recording lock for setting the indicating wheels, a feed actuating means controlled by the lock, circuits adapted to feed the paper to a less extent than the manually operating means, an electro-magnet also controlled by the lock circuits, and connections with both printing pads operated thereby.

2. In a recorder of the kind described, the combination of manually and automatically operated means for independently actuating the recording, the printing and the paper feeding means, of mechanism controlled by either the manual or the automatic means when brought into operation, for locking against operation the other.

3. A combined time autograph and lock recorder, comprising, in combination, the following: a series of time recording type wheels, a series of lock indicating type wheels, a printing mechanism for taking impressions from either or both series of wheels on a paper strip, two feed mechanisms of different capacity, a manual means for operating the printing mechanism and the feed mechanism of greater capacity, automatic mechanism for setting the indicating wheels and for operating the printing mechanism and the feed mechanism of less capacity.

4. In a recorder of the kind described, the combination of two independent paper feeding mechanisms of different throw, a time recording device and a lock recording device, circuits for operating the lock recording and time recording devices and the feed mechanism of shorter throw and a manually operated power shaft for operating the time recording device and feed mechanism of longer throw.

5. In a recorder of the kind described, the combination of the following elements: a paper strip holding means and a window normally closed for exposing a portion of said strip, a time recording device, a lock recording device, feed mechanism for the paper strip and a manually operated power shaft which when turned opens the window and operates the time recording and feed mechanisms, and circuits independently controlling the lock recording and the time recording devices and the paper feed mechanism.

6. In a lock recorder of the kind described, a paper feed, a time recording mechanism, and a lock recording mechanism in combination with a manually operated power shaft for operating the paper feed and the time recording mechanism and an electric motor and circuits from a properly constructed lock for operating the time recording, the lock recording and the paper feed mechanisms.

7. In a lock recorder of the kind de-

70

75

80

scribed, a paper feed, a time recording and a lock recording mechanism in combination with a manually operated means connecting therefrom to and adapted to operate the paper feed and the time recording mechanisms, an electric motor and circuits from a lock and means operated by the motor for actuating both the time recording and the lock recording mechanisms and independent means for operating the paper feed.

8. In a lock recorder of the kind described, the combination with a paper feed

mechanism, lock recording and time recording mechanisms, of a manual means for operating, the paper feed and the time recording mechanisms electrically controlled means for operating the paper feed and both time and lock recording mechanisms and electrically controlled locking means operated by either the manual or the electrically controlled means, to lock the other mechanism when actuated. 15 20

In testimony whereof I affix my signature.

CLINTON E. LARRABEE.
